CLAIM

The ornamental design for a toy riding cycle for children, as shown and described.

DESCRIPTION

FIG. 1 is a left side elevational view of a toy riding cycle for children showing our new design;

FIG. 2 is a right side elevational view thereof;

FIG. 3 is a front perspective view thereof;

FIG. 4 is a rear perspective view thereof;

FIG. 5 is a top perspective view thereof; and

FIG. 6 is a bottom perspective view thereof.

The dot-dash lines in the drawing are to indicate that the tread pattern which has been partially shown is repeated throughout the circumference of the front and rear tires.
